UNITED STATES PATENT OFFICE.

JOHN T. CULLEN AND LESLIE P. GRIMES, OF CLINTON, IOWA.

DESIGN FOR A HEATER.

SPECIFICATION forming part of Design No. 24,712, dated September 24, 1895.

Application filed July 19, 1895. Serial No. 556,515. Term of patent 14 years.

To all whom it may concern:

Be it known that we, JOHN T. CULLEN and LESLIE P. GRIMES, of Clinton, in the county of Clinton and State of Iowa, have invented and produced a new and original Design for a Heater, of which the following is a full, clear, and exact description.

Reference is to be had to the accompanying drawings, forming a part of this specification, in which similar characters of reference indicate corresponding parts in all the figures.

Figure 1 is a broken front elevation of a heater embodying our new design. Fig. 2 is a plan view on a somewhat smaller scale. Fig. 3 is a sectional front elevation; and Fig. 4 is a central transverse vertical section, the doors being omitted.

The leading features of our design reside in the lower or tank portion of the heater, which

is oval, as viewed in plan, and the transversely-disposed arch rising centrally in such oval tank from the bottom of the latter and extending between the front and rear walls thereof. Minor features, supplemental to said leading features, are the top and bottom flanges *a b*, following the oval lines of the tank, the smoke-exit *c* rising above the top of the heater and curving inward at the bottom, and the rectangular doors *e f* within the arched border *g*. 20 25 30

We claim—

The design for a heater, herein shown and described.

JOHN T. CULLEN.
LESLIE P. GRIMES.
